NELSON M. BAKER, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

OPHTHALMIC MOUNTING.

1,244,941.

Specification of Letters Patent.

Patented Oct. 30, 1917.

Application filed April 28, 1917. Serial No. 165,115.

To all whom it may concern:

Be it known that I, NELSON M. BAKER, a citizen of the United States, residing at Southbridge, in the county of Worcester and 5 State of Massachusetts, have invented certain new and useful Improvements in Ophthalmic Mountings, of which the following is a specification.

This invention relates to improvements 10 in ophthalmic mountings and has particular reference to the type of construction commonly known as a fingerpiece, in which the guards are carried by pivoted spring actuated levers, which may preferably be manually operated to facilitate application or 15 removal of the mounting from the face.

One of the leading objects of the present invention is the provision of an improved construction for connecting the lever to the 20 bridge or lens connecting member, which will eliminate the objectionable wear usually occurring at this point of connection, and thus prevent undesirable wabbling or early breakage of the parts of the mounting.

25 A further object of the invention is the provision of an improved construction for this purpose in which the several parts shall be so formed as to be capable of ready construction and so related to each other as 30 to facilitate to a maximum the assembling of the several parts of the mounting in a neat and efficient manner.

Another object of the present invention is the provision of a construction which will 35 accomplish the aforementioned objects and which in addition will have the several parts so united one to the other that they will be located in their assembled position and accidental loosening or separation of 40 the several parts reduced to a minimum.

Other objects and advantages of my improved construction should be readily apparent by reference to the following specification taken in connection with the accompanying drawings forming a part thereof, and it will be understood that I may make any modifications in the specific details of construction shown and described within the scope of the appended claims 45 50 without departing from or exceeding the spirit of my invention.

Figure I represents a front elevation of a mounting embodying my improvement.

Fig. II represents an enlarged vertical

sectional view illustrating the several parts 55 in the process of being assembled.

Fig. III represents a similar sectional view of the several parts in assembled or operative relation.

Fig. IV represents a sectional view of a 60 slightly modified construction of bearing member.

Fig. V represents a similar view of another form of my construction.

Fig. VI represents a sectional view of a 65 modified manner of locking the fastening device.

In the drawings, in which similar characters of reference are employed to denote corresponding parts throughout the several 70 views, the numeral 1 designates the bridge of the mounting being provided at each end with the clips 2 adapted to receive the lenses 3 and having formed intermediate the arched portion of the bridge and the 75 lens engaging clips the flattened portions or pivot seats 4, on which the guard arms or levers 5 are adapted to turn.

In the types of mountings known prior to my invention it has ordinarily been customary to form in the lever 5 a pivot receiving aperture and to pass through said aperture some type of bearing member on which the lever may turn.

This construction, however, has been open 85 to serious objections, in that the lever would wear quite rapidly and would then have a tendency to wabble and rock on the pivot seat, interfering with the proper fit of the mounting on the face, while at the same time 90 the wearing movement of the lever against the pivot member would tend to loosen or unscrew the pivot.

I realize that certain attempts to get away from this difficulty have hitherto been 95 made, and I have myself previously produced commercial constructions in which a longer bearing has been secured by forming a tube or the like integral with the lever and receiving the bearing member. This 100 tube construction, however, while providing a more satisfactory bearing for the lever has not gotten away from the objection experienced, in that the wear is more or less directly upon the pivot member and has a 105 tendency to twist or loosen the pivot.

It is, therefore, the purpose of my present invention to provide an improved construc-

tion which shall embody the several merits of my prior construction and in addition obviate the several difficulties experienced in connection therewith.

5 In the accomplishment of this result, in that form of my construction particularly illustrated in Figs. II and III, I have shown the bridge seat 4 as provided with the pierced aperture 6 extending therethrough and having fitting and suitably secured therein, as by soldering or any other suitable and desirable manner, the tube 7, whose length is slightly greater than the combined thickness of the bridge and of the lever 5 and tube 8 carried thereby, so that the upper end of the tube 7 projects above the upper end of the tube or barrel 8 on the lever. Interiorly the upper portion of the tube 7 is smooth or plain but is provided at its lower end with 15 the inwardly extending threads 9 adapted to engage the threaded portion 10 of the pivot screw 11, having at its upper end the head 12 adapted to fit tightly against the upper end of the tube 7 and extend outwardly over the tube 8 and actuating spring 13 to secure the parts in position.

It will be noted by reference to Fig. II that the length of the screw 11 is such that the lower end can be spun over as at 14 in 20 Fig. III, so that the screw is securely locked in position within the tube and held against any possible accidental loosening thereof, while being capable of ready removal with proper implements when desired.

25 The great advantages of this type of construction should be readily apparent and it will be seen for example when it is desired to assemble the mounting the spring 13 may be placed in position on the barrel 8 which 30 is formed integral with or rigidly connected to the lever 5 and the entire parts readily slipped over the centering tube 7, the spring interlocking with the side of the strap to retain the spring under proper tension and 45 the parts being held together in this position.

The lever having been applied over the upper or free end of the bearing tube 7, it is then merely necessary to drop the securing screw 11 into the tube, when it will slide through the plain portion of the tube and be properly guided and held thereby adjacent the threads, when a few turns of the screw will cause the threads to engage and draw 50 the head of the screw down onto the bottom end of the tube to securely lock the several parts together. The parts being thus connected it is only necessary to spin over the lower end of the screw as at 14 to lock the 55 screw against loosening.

Particular attention is invited to the facility of assembling my present mounting, and particularly to the fact that when placing the pivot screw in position in place of 60 being necessary to work around and get it

into an aperture in the mounting and cause it to be properly guided to work into the threads of the aperture, a difficult operation when holding a lever and spring under tension in position ordinarily, with my improvement it is merely necessary to apply the parts to the mounting and then to drop the screw into place when the tube or bearing member itself forms a guide and retaining device for holding the screw in proper 75 position, and it may be quickly and easily tightened, thus saving considerable time for the assembler and rendering a previously difficult and disagreeable operation a simple and easy one.

It will be understood that various modifications may be employed in the securing of the guide or bearing tube 7 in position in the aperture of the bridge, since it may have an exteriorly threaded portion 15 to engage 85 with threads in the aperture of the bridge and screw down as against the shoulder 16, a notch 17 being provided in the upper end of the tube to receive a screw-driver or the like and facilitate this assembling operation, 90 as illustrated in Fig. IV, or the tube may be inserted in the aperture as is the pivot screw later by the spinning over of the lower end of the tube, as illustrated in Fig. V.

In Fig. VI, I have illustrated a further 95 modification of my invention in which the under face of the bridge may be provided with a socket 18 to receive, or may have bearing directly against its under face without the formation of a receiving socket, the 100 lock nut member 19, which is adapted to be engaged on the lower end of the fastening device 11 and to bear against the under side of the support to securely lock the fastening device in position and prevent accidental 105 disengagement of the fastening device and thus of the parts held thereby.

In connection with the several embodiments of my invention herein described I would call particular attention to the necessity in a construction of this character, not only of providing maximum bearing to allow of easy movement of the parts without undue wear, but also the necessity of securing the several parts in position and preventing accidental loosening thereof.

In structures such as shown in Fig. IV for example where the tube or pivot member 7 is threaded into the bridge, I preferably additionally lock it by spinning over 120 the lower end while with the fastening device 11 for retaining the parts I find it practically essential to the success of the invention that it be suitably locked in place. It is not a question merely of preventing separation and consequent loss of the parts, but of at all times holding the parts against any wobbling or play tending to loosen them. For this reason it is feasible and practicable 125 that the fastening device should have a loose 130

fit in the upper portion of the tube which will serve merely as a guide for the position of the fastening device. It would be entirely possible to let the fastening device pass freely through the entire tube and be locked only by a nut or the like on the lower end by the slight modification of removing the threads shown at the lower end of the tube in Fig. VI, although I find the addition of these threads gives an additional factor of safety in this particular embodiment of my construction, and I wish to here call particular importance to the necessity of in some way locking the fastening device at its lower end to prevent accidental loosening thereof.

I claim:

1. In an ophthalmic mounting, the combination with a bridge having a pivot seat, 20 of a tube secured within the bridge and rising thereabove, a lever having a barrel portion adapted to encircle the tube, an actuating spring for the lever carried by and surrounding the barrel and a fastening device 25 having a head overlying the tube barrel and spring and engaging the tube, said fastening device having a threaded lower end interlocking with the tube for temporarily securing the parts together and having its lower end projecting below the bridge and tube and spun over thereagainst to permanently lock the parts in assembled relation.

2. In an ophthalmic mounting including a bridge, a pivot tube rising from the bridge, 35 a lever mounted on the pivot tube and having a barrel encircling the tube, means for actuating the lever, and a fastening device having a head on its upper end limiting upward movement of the lever and barrel portion to the tube and having its lower end extending downward through the tube and bridge and provided with an enlargement to prevent accidental loosening of the fastening device.

45 3. In an ophthalmic mounting, the combination with a bridge having a tube extending therethrough and projecting from one side thereof, of a lever turning on the bridge and having a barrel thereon encircling the 50 tube, the upper portion of the tube being unthreaded and the lower portion thereof having inwardly extending threads and a head-

ed fastening device having its head extending over the upper face of the tube and barrel, its lower portion in interlocking threaded engagement with the threaded interior of the tube and its lower end spun or enlarged and bearing against the under side of the tube or support to securely lock the fastening device in position.

4. In an ophthalmic mounting, the combination with a supporting member having an aperture therethrough, of a tube rising from the support at the aperture, a lever pivoted on the tube and having a barrel portion 65 encircling the tube, a fastening device loosely inserted in the tube, and means for engaging the lower end of the fastening device to secure the lever in position on the tube.

5. In a device of the character described, the combination with a support having an aperture therethrough, of a tube rising from the support at the aperture, a lever pivoted on the tube and having a barrel portion 75 encircling the tube, an actuating spring for the lever encircling the barrel portion, a headed fastening member loosely inserted in the tube, the span of the head being sufficient to prevent removal of the spring or barrel 80 thereover, and means for engaging the lower end of the fastening device to retain the same in position.

6. In a device of the character described, the combination with a support, of a tube 85 rising therefrom, the bore of the tube extending through the support, a lever having a barrel portion pivotally mounted on the tube, an actuating spring for the lever encircling the barrel portion thereof, a fastening device for the parts loosely fitting within the upper portion of the tube and of length to depend through and project below the support, and means on the lower end of the fastening device adapted to engage the 90 under face of the support to lock the fastening device in position.

In testimony whereof I have affixed my signature, in presence of two witnesses.

NELSON M. BAKER.
